UNITED STATES PATENT OFFICE.

CHARLES E. ELM, OF SOUTH PRAIRIE, WASHINGTON.

RAIL-JOINT.

No. 869,164.

Specification of Letters Patent.

Patented Oct. 22, 1907.

Application filed January 30, 1907. Serial No. 354,872.

To all whom it may concern:

Be it known that I, CHARLES E. ELM, a citizen of the United States, residing at South Prairie, in the county of Pierce and State of Washington, have invented new and useful Improvements in Rail-Joints, of which the following is a specification.

This invention relates to rail joints, the object of the invention being to provide a practical support for the contiguous ends of railway rails whereby said rails are prevented from breaking down at the joints, the improved device being applicable to rails already in place without removing the fish-plates or splice bars and without in any way disturbing the construction of the road-bed.

With the above general object in view, the invention consists in the novel construction, combination and arrangement of parts hereinafter more fully described, illustrated and claimed.

In the accompanying drawings, Figure 1 is a sectional plan view of a rail joint showing the device of this invention applied thereto. Fig. 2 is a side elevation of the same. Fig. 3 is a sectional side elevation thereof. Fig. 4 is a cross-section taken on the line 4-4 of Fig. 2. Fig. 5 is a cross-section taken on the line 5-5 of Fig. 3.

In Fig. 1, I have shown an ordinary rail joint in which 1 and 2 designate the rail ends, and 3 the splice bars or fish-plates applied thereto and corresponding with those at present in use.

In carrying out the present invention, I employ two rail clamps for each rail joint, one of said clamps being illustrated in elevation in Fig. 4, in which it will be seen that the clamp comprises two sections 4 and 5, the section 4 having its body made long enough to extend beneath both flanges of the rail and being provided with a lip 6 which overhangs one of the rail flanges and serves as a connection between said section of the clamp and the rail for properly supporting the clamp on and from the rail. The section 4 is also provided with a horizontal extension 7 upon which the body of the other clamp section 5 rests and to which it is attached. The section 5 is provided with an overhanging lip 8 corresponding in shape and function with the lip 6. The two clamp members are further provided with interlocking tongues and grooves 9 so that they may be properly aligned one with the other to bring the same into proper relation to each other and to the rail. The sections 4 and 5 are further provided with outwardly extending lugs or rests 10 for the support of the extremities of a pair of truss-bars 11 and

12 arranged at opposite sides of the rail ends 1 and 2, as shown in Fig. 1.

Each of the truss-bars 11 and 12 comprises an arched body 13, highest at the center and tapering therefrom toward each end, the central portion of the body being approximately as high as the lower sides of the heads of the rails, as indicated in Fig. 2. Each truss-bar also comprises the oppositely extending reinforcing flanges 14 located in the plane of the bottom of the body 13 of the cross-bar and the outer flanges 14 are extended far enough to provide terminal ears 15 which bear upon the rests 10 of the clamps 4 and 5 and are bolted or otherwise secured thereto as indicated at 16. The inner flange of each truss-bar is preferably cut away as shown at 17 to allow for the adjacent overhanging lip 6 or 8 of the clamp sections.

The central portions of the truss-bars are enlarged or widened as shown at 18 to form broad bearings against and upon a rail end seat 19 provided with a bottom reinforcing flange 20 to give the requisite strength thereto. This seat 19 extends transversely beneath the extremities of the rails, as best indicated in Figs. 2 and 3, the body of the seat resting in contact with the bottoms of the rails, as shown in Fig. 3, and the truss-bars are firmly secured thereto by bolts or their equivalent, as indicated at 21. It will thus be seen that the truss-bars are supported at their opposite extremities by means located at points remote from the rail extremities and that the truss-bars in turn support the rail end seat 19 which extends beneath the extremities of the rails and prevents the breaking down of the rails at their joints.

It will also be noted that the device hereinabove described is applicable to a railway without removing the fish-plates or otherwise disturbing the road-bed construction.

I claim:—

1. A rail end support comprising a truss-bar disposed above the bottom of the rails, means located at opposite sides of the rail extremities for supporting the truss-bar, 90 and a seat for the rail extremities supported by said truss-bar.

2. The combination with rail ends, of rail clamps located at opposite sides of said extremities, a truss-bar disposed above the bottom of the rails and having its 95 opposite ends supported by said clamps, and a rail end seat supported by the truss-bar at a point intermediate the ends of the latter and extending beneath the rail extremities.

3. The combination with rail ends, of truss-bars arranged 100 at opposite sides thereof and in a common horizontal plane therewith, means for supporting the ends of said truss-bars

at points remote from and on opposite sides of the rail joint, and a rail end seat supported on and underneath said truss-bars and extending beneath the extremities of the rails.

5 4. The combination with rail ends, of secondary clamps secured to the rails at points remote from and on opposite sides of the joint, parallel truss-bars supported above the bottom of the rails and having their ends supported by said clamps, and a rail end seat supported by said truss-

bars at a point intermediate the ends of the latter, said 10 seat extending beneath the rail extremities which rest thereon.

In testimony whereof, I affix my signature in presence of two witnesses.

CHAS. E. ELM.
